D7-506

EX

D9532

OR D 14,758

UNITED STATES PATENT OFFICE.

CHARLES E. HAVILAND, OF LIMOGES, FRANCE.

DESIGN FOR A DISH.

SPECIFICATION forming part of Design No. 14,758, dated February 19, 1884.

Application filed July 30, 1883. Term of patent 14 years.

To all whom it may concern:

Be it known that I, CHARLES E. HAVILAND, a citizen of the United States, residing in the city of Limoges, Republic of France, have invented and produced a certain new and original Design for Dishes Constituting a Table-Service, fully described and represented in the following specification and the accompanying illustrations, forming a part of the 10 same.

Said illustrations show so many of the dishes of a table-service as are necessary to exhibit the general application of the design, Figure 1 representing a salade; Fig. 2, a plate; Fig. 15 3, a dish; Fig. 4, a platter; Fig. 5, a sauce-boat and stand, and Fig. 6 a cup and saucer.

The principal characteristic of the design is a simple leaf, preferably with multicostate veining, whose blade expands into a 20 somewhat oblong form, and exhibits a multiplicity of lobes at the margin. The edge of each of these lobes is given a sinuous crisspated form, while an oval shape of the dish, when viewed vertically, is maintained. The stem appears 25 extending from one to the other of two of the lobes as a handle. The veining and the stem may, however, be omitted. The number of the lobes may be varied without departing from the generic nature of this design; but 30 a good practical embodiment of it embraces the five lobes shown. These five lobes are marked A as near their centers as may be, and though some are more extended than others, all are clearly distinguishable. The stem B, 35 hidden from view, as applied to the sauce-boat stand in Fig. 5, is omitted from the sauce-boat, (same figure,) and from the saucer, Fig. 6, as it may be from all the dishes, if desired. This stem B, supposed to join the leaf at its 40 base C, from whence the veins are generated, (best shown in Fig. 4,) is curled, so as to protrude between two lobes A and form a handle, and may, if desired, be extended to surround the base and form a foot, as in Fig. 1, where 45 it is marked a second time with the letter B, to indicate this disposition of it. The sinuated crisspated edges of the lobes A have their twisted, bent, curled, wavy form best illustrated in Figs. 1, 3, 4, and 6. In Fig. 4 the

elongated dish is formed by a partial duplication of the design—that is to say, one leaf, marked I, is shown as laid over a second leaf, marked II, and this dish is provided with a drainer, D, having the characteristics of this design. 50

Dishes of this design, made more or less oblong and more or less deep, will constitute all the dishes of a table-service, and may be left open or provided with covers, as is well understood. 55

Various fanciful surface ornamentation is shown, and this may be varied as taste may dictate or trade demand. The design, however, will be preserved, whether the goods remain white, or are tinted, shaded, or otherwise decorated. 60

The specific design for dishes shown in Fig. 4 is disclaimed herein, as it forms the subject-matter of a separate application.

What is herein claimed is—

1. The design for the dishes of a table-service, the same consisting of a dish having the configuration of a leaf or leaves exhibiting a blade that involves a multiplicity of lobes having a sinuous crisspated edge, and constituting a general oval shape, substantially as shown and described. 75

2. The design for the dishes of a table-service, the same consisting of a dish having the shape or configuration of a leaf or leaves exhibiting a five-lobed blade having a sinuous crisspated edge, substantially as shown and described. 80

3. The design for the dishes of a table-service, the same consisting of a dish having the shape or configuration of a leaf or leaves exhibiting a blade having a multiplicity of lobes, and a stem extending from one to the other of two of said lobes, substantially as shown and described. 85

In testimony whereof I have hereunto set my hand in the presence of two subscribing witnesses.

CHARLES ED. HAVILAND.

Witnesses:

E. CANDEAU,
T. CATE.
